UNITED STATES PATENT OFFICE.

WILLIAM H. HOESCHEN AND JOSEPH A. HOESCHEN, OF OMAHA, NEBRASKA.

MECHANICAL MOVEMENT.

1,213,771.

Specification of Letters Patent. Patented Mar. 13, 1917.

Application filed November 23, 1916. Serial No. 132,941.

To all whom it may concern:

Be it known that we, WILLIAM H. HOESCHEN and JOSEPH A. HOESCHEN, citizens of the United States, residing at Omaha, in the 5 county of Douglas and State of Nebraska, have invented certain new and useful Improvements in Mechanical Movements, of which the following is a specification.

This invention relates to a mechanical 10 movement which may be employed for a variety of useful purposes where a limited longitudinal movement of an actuating rod or bar is desired, and to be caused by pressure of an object upon an inclined part of 15 the actuating bar or upon a wedge bearing upon said rod, the movement to be uniform and unaccompanied by vibration.

The invention is illustrated in connection 20 with a horizontally disposed actuating bar and wedge to be moved by vertical pressure applied to a track rail, since it is useful in connection with signaling or indicating passing or moving trains, or for the operation of switches, semaphores, or electric generators, but obviously it may be used for 25 other purposes and may be employed in instances where the pressure is applied horizontally, the actuating bar being disposed substantially at right angles to the longitudinal 30 axis of the wedge.

The invention consists of the novel construction, combination and arrangement of parts as described herein and claimed, and as illustrated in the accompanying drawing, 35 wherein,—

Figure 1 is a view of a frame or casing in side elevation for containing certain operating parts, one of the side plates being removed and parts being broken away and in 40 section, a track rail being shown in transverse section. Fig. 2 is a transverse section on line 2-2 of Fig. 1. Fig. 3 is a view on an enlarged scale showing the tubular plungers in longitudinal section. Fig. 4 is a side view 45 of a pair of side bars.

Referring now to the drawing for a more particular description, numeral 4 indicates a stationary part or support, upon which is mounted a casing 5 of any suitable form, but 50 shown herein to be, and preferably being rectangular in plan, and having a compartment 6 opening upon one of its ends, said compartment being provided with an aperture 7 in its end wall 8.

At 9 is indicated a rectangular plate of

uniform thickness disposed in the casing, and which may be dispensed with if desired, but is employed as a matter of convenience, since its upper surface should be smooth and rectilinear. Upon the plate 9 are disposed a 50 plurality of rollers 10 maintained parallel with reference to each other and at right angles to the plate by means of the pair of side bars or yokes 11 which are disposed in recesses 12 opening upon the inner faces of 55 the sides 13 of the casing, said members 10 being limited in their rolling movements in one direction by the pair of screws 14 with which the plate 9 is provided.

Upon the rollers 10 is disposed a wedge 15 70 having smooth upper and lower sides for engaging the rollers and having its part of greatest thickness disposed adjacent to the compartment 6, and having a head or stem 16 of such form or proportion that it may, 75 upon occasion, enter the compartment 6. Numeral 17 indicates a plurality of rollers disposed upon the upper side of the wedge, these being similar to the first named rollers, and preferably having their ends pivotally mounted in the pair of side bars 18, these being also disposed in recesses 12; and at 19 is indicated a second wedge, its lower side, which bears upon the rollers 17, having 80 a smooth rectilinear surface, said member 19 being provided with a pair of screws, 85 a for discharging the same function as the screws 14, the part of greatest thickness of the wedge 19 being disposed at the end of the casing, opposite to the compartment 6. 90

At 20 is indicated an actuating rod or bar disposed in line with and preferably having its inner end secured to the head 16, a spring 21 being employed for resisting a movement of this wedge in a direction of the compartment 6. 95

Numeral 22 indicates an element to which a pressure may be applied for causing a longitudinal movement of the wedge 15 in a direction of the compartment 6 and for moving the rod 20 outwardly of said compartment. 100

The top of the casing at its middle is provided with a boss or collar 23 in which is seated a tubular plunger 24 having its upper end in engagement with member 22, said plunger being provided interiorly thereof with a downwardly projecting pintle 25. Numeral 26 indicates a second tubular plunger disposed in the plunger 24, its upper 110

end being mounted upon the pintle above a keeper 27, said keeper being threaded upon the lower end of the pintle.

On account of the construction as described, the lower end of the plunger 26 is in constant engagement with the middle part of member 19 on account of the action of a spring 28 which is interposed between the plungers. It will be noted that the plunger 24 may slide until its lower end engages the wedge 19, also that the boss or collar 23 is well adapted to support all transverse stresses. The tubular plunger 26 may freely slide upwardly within the plunger 24 subject to the resistance of the spring 28. Also, during operation the wedge 15 will have a uniform movement outwardly and inwardly of the casing, the rollers, on account of their connection with the side bars moving uniformly therewith while bearing upon the smooth surfaces of members 9 and 19.

The resistance provided for the spring 28 may be adjusted by means of the threaded connection of the keeper 27 with the pintle, and for most purposes this adjustment is such that the plunger 26, when a pressure is applied to the plunger 24 by member 22, will not immediately move upwardly within the plunger 24 while the wedge 15 is moving outwardly, but if an excessive or undue pressure is applied to said member 22, the spring 28 may be compressed, the result being that all shocks and practically all vibration delivered to the plunger 22 from member 22, will be neutralized by the spring 28.

The arrangement of parts is such that the device may be used in instances where a limited movement only of the actuating rod is required, as for moving an electrical contact member for making or breaking an electrical circuit (not shown), or in other instances to provide for an extended thrust or movement of the actuating rod.

Any suitable means may be provided for interlocking the side bars of each pair, such as the recess 29 formed in one side bar, best shown in Fig. 4, adapted to be engaged by a finger 30 of the other side bar of the same pair.

Having fully described our invention, what we claim and desire to secure by Letters Patent is,—

1. A mechanical movement, comprising, in combination, an upper plate, a lower plate, a wedge between the plates and provided with an actuating rod projecting outwardly of the plates, a plurality of rollers disposed between and engaging the wedge and lower plate, a plurality of rollers disposed between and engaging the wedge and upper plate, and an element arranged to press one of the plates toward the other plate for moving the wedge and actuating rod longitudinally of the plates.

2. A mechanical movement comprising, in combination, two adjacently disposed plates, a wedge therebetween and provided with a projecting part, rollers interposed between the plates and wedge, and an element arranged to press one of the plates toward the other plate to move the rollers in the same direction longitudinally of the plates and to move the wedge outwardly of said plates.

3. A mechanical movement comprising a pair of adjacent plates, a wedge between the plates, rollers between the wedge and said plates, and a pressure element for moving the wedge longitudinally of the plates, one of said plates moving toward the other plate while the wedge is moving in one direction and moving away from the other while the wedge is moving in a reverse direction.

4. A mechanical movement comprising, in combination, two adjacently disposed plates, a wedge therebetween, rollers interposed between the plates and wedge, a pressure element for moving one of the plates transversely toward the other plate to move the rollers in one direction and to move the wedge outwardly of said plates, and a resilient member interposed between the pressure element and one of said plates.

5. A mechanical movement comprising, in combination, a support, a plate on the support, a second plate adjacent to the first named plate, a wedge between the plates, connected side bars arranged in pairs at the opposed side edges of the plates and wedge, rollers journaled at their respective ends upon a side bar of each pair and disposed between the first named plate and the wedge, rollers journaled at their respective ends upon a side bar of each pair and disposed between the second plate and the wedge, and an element arranged to press one of the plates transversely toward the other plate for moving the wedge longitudinally of said plates.

6. In a mechanical movement, in combination, a casing provided with a bottom and having recesses in its sides, a plate in the casing, a wedge in the casing between the bottom and said plate, side bars arranged in connected pairs, each pair being disposed in a recess, rollers engaging the bottom of the casing and wedge and having their ends journaled in one of the side bars of each pair, rollers engaging the plate and wedge and having their ends journaled in one of the side bars of each pair, and an element adapted to press the plate toward the bottom of the casing for moving the wedge longitudinally.

7. In a mechanical movement, in combination, a lower plate, an upper plate, a wedge between the plates, resilient means tending to prevent a movement of the wedge, journaled rollers engaging the wedge and lower

plate, a plurality of journaled rollers engaging the wedge and upper plate, a pressure element engaging the upper plate to move said upper plate transversely toward the lower plate for moving the wedge, and a resilient member between the pressure element and upper plate.

8. In a mechanical movement, the combination of a stationary plate, a secondary plate disposed above the stationary plate, a wedge between said plates, connected bars disposed at opposed sides of the plates and wedge, rollers having their respective ends

journaled in said bars and disposed between the inclined faces of the wedge and said plates, and an element pressing the secondary plate toward the stationary plate for moving the connected bars, rollers and wedge in one direction.

In testimony whereof, we have affixed our signatures in presence of two witnesses.
